UNITED STATES PATENT OFFICE.

ARTHUR W. KEWLEY, OF ATLANTIC, IOWA.

CONDENSER FOR RADIATOR CAPS.

Application filed May 29, 1923. Serial No. 642,272.

This invention relates to radiator caps and aims to provide novel means for condensing the steam usually generated by a motor, when the same becomes overheated, the steam usually passing off through an overflow pipe.

Another object of the invention is to provide a device of this character which will conserve the water contained in the radiator with which the device is associated, thereby reducing the chances of the water supply of a motor becoming exhausted, to the minimum.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:—

Figure 1 is a front elevational view of the upper portion of a radiator disclosing a cap constructed in accordance with the present invention as applied.

Figure 2 is an enlarged detail view of the cap, portions thereof being broken away.

Figure 3 is a sectional view taken on line 3—3 of Figure 2.

Referring to the drawing in detail, the reference character 5 indicates a radiator cap to which the attachment forming the subject matter of the present invention is applied.

The cap is formed with a central opening to receive the threaded stem 6 of the body portion 7 of the attachment, the stem 6 being hollow as at 8 to allow steam generated in the cooling system to pass upwardly therethrough.

This body portion is preferably circular in formation, and has integral curved hollow condenser tubes 9 that have their upper extremities curved outwardly as at 10 to increase the lengths of the tubes 9 and at the same time lend distinction to the attachment.

As shown, the condenser tubes curve outwardly at a point adjacent to the body portion 7 providing a circular space to accommodate disks 11 that are held in spaced relation by their engagement with the opposite sides of the lugs 12, the disks being held in position on the lugs 12 by means of the bolts 13 that extend through suitable openings in the lugs and disks.

These disks may be employed for receiving the name plate of a motor vehicle or identification plate the construction being such as to enhance the appearance of the usual motor radiator cap and at the same time act to condense the steam arising in the condenser tubes.

In view of the fact that a draft of air will be created at the forward portion of a motor vehicle when the same is moving over a road surface, it is obvious that the air will have a cooling effect on the tubes 9 to condense the steam entering the tubes, whereupon the condensates will be returned to the radiator to which the device is applied.

A nut indicated at 15 is positioned on the threaded stem 6 and provides means cooperating with the head 7 to cause the radiator cap to be clamped between the head and nut 15 to secure the device to the cap.

I claim:—

In a condenser for use in connection with motor vehicle radiators, a body portion having integral upwardly and outwardly curved tubes, the upper extremities of the tubes extending an appreciable distance above the body portion and curved outwardly, said tubes being closed at their free ends, a pair of spaced disks supported between the tubes, the peripheries of the disks lying in spaced relation with the tubes to permit air to pass therethrough.

In testimony that I claim the foregoing as my own, I have hereto affixed my signature.

ARTHUR W. KEWLEY.
